Attorney

UNITED STATES PATENT OFFICE

HARRISON J. L. FRANK, OF DETROIT, MICHIGAN, ASSIGNOR TO MUTUAL ELECTRIC AND MACHINE COMPANY, OF DETROIT, MICHIGAN, A CORPORATION OF WEST VIRGINIA

METERING PANEL

Application filed October 23, 1922. Serial No. 596,292.

- This invention relates to electric systems for large office buildings and other structures where a number of tenants are individually supplied with electric current, and its object is to provide an installation of this character which may be entirely locked to the general public and which shall be so enclosed that certain portions such as the compartment containing the circuit switches and fuses shall be accessible to all persons having to do with the electric service of the building while other portions such as the meter connections shall be accessible only to persons delegated thereto by the electric service corporation.
- Another object of this invention is to provide simple means whereby the circuit switches of different rooms or suites of a building may be connected to a single meter.
- Another object of this invention is to provide means so that the wires to and from the meters can be kept separate from the circuit wires.
- Another object of this invention is to produce a complete metal-enclosed system of wiring between the wires of the service company and the meters which indicate the consumption of current, every part of the system being enclosed and sealed to prevent tampering.
- This invention consists in the details of construction illustrated in the accompanying drawings and particularly pointed out in the claims.

In the accompanying drawings, Fig. 1 is a front elevation of a metering panel embodying the present invention. Fig. 2 is a section on the line 2—2 of Fig. 1. Fig. 3 is a section on the line 3—3 of Fig. 2. Fig. 4 is a front elevation of a switch and the connections thereto. Fig. 5 is a transverse section showing a sealing device. Fig. 6 is a section of a corner of a case on a larger scale. Fig. 7 is a perspective of a connector. Fig. 8 is a perspective of a tagging device. Fig. 9 is a front elevation of a metering panel on a smaller scale with parts of the doors broken away.

Similar reference characters refer to like parts throughout the several views.

Metering panels are installed in office build-

ings, apartment houses and other structures where a number of persons pay individually for the current consumed and where such persons are liable to enlarge or reduce the quarters occupied. Provision must therefore be made to group the circuit wires of any possible group of rooms on one meter and these wires must be safeguarded so that unauthorized tampering with them will be prevented. As apartments or suites of rooms may be subdivided in the future, provisions must be made for the installation of additional meters as they shall be needed. Provision must also be made to permit replacement of burnt fuses by a person who is not authorized to change the wires to the meters so that doors must be provided giving access to the various portions of the metering panels.

The metering panel shown in the drawings is enclosed in a case which has a back 1, sides 2 and 3, top end 4 and lower end 5, preferably of metal. Mounted in this case is a base 6 of non-conducting material to which are attached the side walls 7 and 8, the top wall 9, the bottom wall 10, the long transverse wall 11 which cuts off the main switch from the remainder of the circuits, the upright partition walls 12 and 13 which separate the compartments containing the private or circuit fuses and switches from the central compartment, and the short walls 14 which constitute the lower walls of the private fuse compartments. Extending from the bottom 1 and parallel to the sides 2 and 3 are partition walls 15 and 16 which may also be of metal, and which are between the spaces or troughs for the house wires from the troughs for the meter wires. The walls 7 and 8 and any of the other walls may be reinforced by the angle bars 21 shown in Fig. 2.

A pipe 17 extends through the bottom end 5 and the main wires 18, 19 and 20 extend through the pipe 17 and openings in the wall 10 to the main fuses 22, 23 and 24. The main switch 25 connects these fuses to the bars 26, 27 and 28. The bar 27 is the feed wire terminal and extends to near the wall 9 beneath a plate 30 and smaller conductors 31 extend from this main terminal to terminals of the

circuit switches. The bars 26 and 28 are meter-terminal bars.

Mounted on the slab 6 between the walls 7 and 12 and the walls 8 and 13 are circuit switches 32 and fuses 33 and 34 of any desired types. Circuit wires 35 lead from these fuses to the conventionally indicated points of consumption of current 36 while wires 37, 38, 39 and 40 lead to the meters 41, 42, 43 and 10 44 respectively. Other wires 45, 46, 47 and 48 extend from these meters to the protective fuses 80 which connect to the meter-terminal bars 26 and 28. In order to prevent 15 tampering with the meter connections outside of the metering panel, the elbows 49 are provided, being attached to the sides 2 and 3 and are formed to receive the lower ends of the meters. The usual shunt wires 90 are provided for meters requiring the same and 20 these connect to the main feed circuit connector bar 27 at a point where these are placed under seal.

Each portion of this panel can be sealed. As indicated in Fig. 9, a main front plate 51, 25 is attached to the meter panel after all the circuit wires 35 have been installed and attached to their respective fuse terminals. There is no occasion for changes after the initial installation. Side doors 52 give access 30 to the meter troughs and these doors may be secured by the seals 53. The main upper door 54 gives access to the circuit switches and circuit fuses so that these can be replaced when blown out. This door is 35 preferably hinged to the cabinet so that one man can gain access to the switches and fuses. Where the door must be removed entirely, several men are often necessary to lift the heavy fronts into place. The meter wires 40 are covered by a door 55 and a plate 56, both of which are sealed. Removable bridges 57 extend between the walls 7 and 15 and between the walls 8 and 16 above the circuit wires and through them the meter wires extend 45 across the circuit wires. These bridges have bottoms 58, sides 59 and end flanges 60 and 61 to position them in the partition walls.

A second outer door 63 covers the main switch 25 and the fuses 22, 23 and 24 together 50 with the meter-terminal bars 26 and 28 and the meter protective fuses 81, or any desired substitutes therefor.

It is thus apparent that the janitor or engineer of a building may be in position to 55 open the door 54 to renew the circuit fuses and open or close the circuit switches. The front door frame 51 prevents access to the circuit wires and the inner door 55, cross plate 56 and side doors 52 prevent access to the meter wires by all who are not authorized 60 to break the seals. It is presumed that the door 63, which is capable of being both locked and sealed, will usually be locked and maintained locked by the lighting company. And 65 it is also presumed that the service fuses and

the meter fuses contained in this section are fuses much heavier than the circuit fuses contained in the upper section. Therefore, these service fuses and meter fuses should not blow except under rare conditions and in this event 70 the lighting company would send its service man to replace these fuses. Should the lighting company not deem this necessary, they could then make the fuses available to the engineer or janitor by opening the door. 75

In Figs. 5 and 6 I have shown several forms of seals. In Fig. 5 the two partitions 11 and 14 are shown provided with angle bars 65 at their upper edges which carry the screws 66 which secure the plate 56 in position. The seal wires 67 extend through holes in these screws and in the screws 68 and thus prevent removal of this plate. 80

In Fig. 6, the side wall 3 has its upper edge 70 turned inward to receive the door 52 and the wire 71 extends through holes in this door and wall. The screw 72 extends through both door and wall and the nut 73 thereon is secured by the wire 74 and seal 75. 85

In Figs. 1 and 2 the switches 31 are shown 90 to have terminals 77 extending up along the walls 12 and 13 to the bolts 78 which have nuts 79 on their inner ends. When two or more of these switches are to be connected to a meter, the connector bars 80 are employed, these bars having notches 81 to receive these bolts. It is evident that these bars may be made of any desired length or any number of them may be overlapped to unite the switches for a meter. These bars 95 and the terminals to which they are connected are preferably spaced a distance from the plate 30 so as to be accessible when this compartment is filled with wires. 100

I have indicated the wires 45 and 48 and 105 the wires 37 to 40 by lines of different character. In practice, the wires for each meter will have a covering of a distinctive color or combination of colors so that they can be followed without difficulty. This may also be the case with the circuit wires 35. As a further aid to identification, a small plate 83 (Figs. 4 and 8) may be attached to each switch and this plate may be painted or have a short piece of the meter wire attached to it so that the meters can be checked or tested by a test meter connected to the proper terminals, and the various circuits that are grouped on a certain meter can be identified without opening the sealed compartments. 115

It may be found desirable to have means 120 for identifying the meter circuits in plain view on the meters and therefore a receptacle or plate 85 is provided on the front of each meter to receive the identifying marks similar to the marks on the plate 83 or short pieces of the meter circuit wires may be mounted in the receptacle and covered with a transparent plate if desired. This system 125 or code of wires and identifying devices en- 130

ables the line-men to quickly select the wires pertaining to each meter and to each tenant's circuit and thus not only saves much time but also reduces the chances for mistakes.

5 Stranded cables having each strand insulated and of a particular color or otherwise identified may often be used to advantage. The identification tags 85 may be placed in the brackets 49 or elsewhere adjacent the meters 10 should marking the meters themselves be found inconvenient.

The details of construction and the proportions of the parts of this metering panel may all be changed by those skilled in the art without departing from the spirit of my invention as set forth in the following claims.

I claim:—

1. In a metering panel cabinet, a central compartment, bus bars and circuit controlling appliances within the central compartment, partitions, within the cabinet, segregating two parallel wiring gutters between each cabinet side wall and the central compartment, circuit wires within each inner gutter 20 and meter wires within each outer gutter, and a trough communicating between each outer gutter and the central compartment, the meter wires in the outer gutters leading to the appliances in the central compartment 25 through the troughs.

2. In a metering panel cabinet, a central compartment, bus bars and circuit controlling appliances within the central compartment, partitions within the cabinet, segregating 30 two parallel wiring gutters between each cabinet side wall and the central compartment, circuit wires within each inner gutter and meter wires within each outer gutter, and a trough communicating between each outer 35 gutter and the central compartment, the meter wires in the outer gutters leading to the appliances in the central compartment through the troughs, and a cover hinged over said compartments and troughs, said cover 40 being divided into sections with one of said sections covering the central compartment and other sections covering said gutters and troughs.

3. In a metering panel cabinet, a central 50 compartment, bus bars and circuit controlling appliances within the central compartment, partitions, within the cabinet, segregating two parallel wiring gutters between each cabinet side wall and the central compartment, circuit wires within each inner gutter 55 and meter wires within each outer gutter, troughs communicating between the outer gutters and the central compartment, the 60 meter wires in the outer gutters leading to the appliances in the central compartment through the troughs, said central compartment being further divided into two portions in one of which are located the main 65 leads, main fuses and main switch while the

other includes the controlling appliances for the meter circuits.

4. In a metering panel cabinet, a central compartment, bus bars and circuit controlling appliances within the central compartment, partitions within the cabinet, segregating two parallel wiring gutters between each cabinet side wall and the central compartment, circuit wires within each inner gutter and meter wires within each outer gutter, and a trough communicating between each outer gutter and the central compartment, the meter wires in the outer gutters leading to the appliances in the central compartment through the troughs, said central compartment being further divided into a plurality of portions, and a separate sealing means for each portion.
